UNITED STATES PATENT OFFICE.

FAYETTE A. BILLMEYER, OF PITTSBURGH, PENNSYLVANIA.

DESIGN FOR A TOY.

58,699.

Specification for Design.

Patented Aug. 30, 1921.

Application filed March 21, 1921. Serial No. 454,297. Term of patent 14 years.

To all whom it may concern:

Be it known that I, FAYETTE A. BILLMEYER, a citizen of the United States, residing at Pittsburgh, Allegheny county, Pennsylvania, have invented new, original, and ornamental Design for Toys, of which the following is a specification, reference being had to the accompanying drawing, forming part thereof.

The figure is a perspective view of a toy showing my new design.

I claim:

The ornamental design for a toy, as shown.
FAYETTE A. BILLMEYER.
